UNITED STATES PATENT OFFICE.

JULIUS M. HEYMAN, OF NEW YORK, N. Y.

DESIGN FOR AN UNDERSHIRT.

SPECIFICATION forming part of Design No. 25,342, dated March 31, 1896.

Application filed December 30, 1895. Serial No. 573,839. Term of patent 14 years.

To all whom it may concern:

Be it known that I, JULIUS M. HEYMAN, a citizen of the United States, residing at the city, county, and State of New York, have 5 invented and produced a new and original Design for Undershirts, of which the following is a specification, reference being had to the accompanying drawings, forming part of the same.

10 The leading feature of my design consists in the design in its entirety, substantially as herein shown and described.

In the drawings, Figure 1 is a front view of the shirt when closed, and Fig. 2 a like view 15 of the same partly opened.

A represents the inner flap of the shirt, and B the outer flap, both flaps being substantially the same in contour, substantially the same in width and length, and substantially 20 the same width and length as the back of the

shirt. The inner flap A is provided on one side with a row of buttons *a*, and the outer flap B has buttonholes *b* in its outer edge. The outer corners of the inner flap A are provided with buttons *a'*, and the outer flap B 25 has buttonholes *d'* in its corresponding portion. In the upper edges of the flaps A and B are central yokes *e f*, and the sides and top edges of the flap B have reinforcing-strips C. Adjacent the yoke in the flap A are buttons 30 *c c*, and adjacent the yoke in the front B are buttonholes *d d* alining with the buttons *c c*.

I claim—

The design for an undershirt, substantially as herein shown and described.

JULIUS M. HEYMAN.
